CLAIM

The ornamental design for a knife and associated sheath, as shown and described.

DESCRIPTION

FIG. 1 is a perspective view of the knife and associated sheath shown in a first position of use, wherein a portion of the knife is located within the sheath;

FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof;

FIG. 7 is a bottom plan view thereof;

FIG. 8 is a perspective view of the knife and associated sheath shown in a second position of use, wherein the knife is spaced from the sheath;

FIG. 9 is a front elevation view thereof;

FIG. 10 is a rear elevation view thereof;

FIG. 11 is a left elevation view thereof;

FIG. 12 is a right elevation view thereof;

FIG. 13 is a top plan view thereof;

FIG. 14 is a bottom plan view thereof;

FIG. 15 is a perspective view of the knife and associated sheath interconnected to a bracelet shown in a first position of use, wherein a portion of the knife is located within the sheath;

FIG. 16 is a front elevation view thereof;

FIG. 17 is a rear elevation view thereof;

FIG. 18 is a left elevation view thereof;

FIG. 19 is a right elevation view thereof;

FIG. 20 is a top plan view thereof;

FIG. 21 is a bottom plan view thereof;

FIG. 22 is a perspective view of the knife and associated sheath interconnected to a bracelet shown in a second position of use, wherein the knife is spaced from the sheath;

FIG. 23 is a front elevation view thereof;

FIG. 24 is a rear elevation view thereof;

FIG. 25 is a left elevation view thereof;

FIG. 26 is a right elevation view thereof;

(Continued)

FIG. 27 is top plan view thereof; and,
FIG. 28 is a bottom plan view thereof.
The broken lines depict environment and form no part of the
claimed invention.
